UNITED STATES PATENT OFFICE.

JOHN D. WALSH, OF NEW YORK, N. Y., AND LOUIS C. ANTRIM, OF JERSEY CITY, NEW JERSEY; SAID ANTRIM ASSIGNOR TO WALTER F. WALSH, OF BOSTON, MASSACHUSETTS.

MANIFOLDING CONTAINER DEVICE.

Application filed December 8, 1926. Serial No. 153,362.

It is an object of our invention to design a container for multiple form record use which can also be used as an operating portion or register such as is usually connected with the use of multiple forms. Thus we eliminate the necessity of a separate machine. It is also our object to design this container so that it will be very inexpensive and yet be simple in its operation. Our invention will be more readily understood by reference to the accompanying drawings in which like letters refer to like parts in the several views.

Fig. 1 shows a perspective view with a section of the outer cover removed. Fig. 2 shows a sectional side elevation through the plane 2—2. Fig. 3 shows an end cross section elevation through the plane 3—3.

Referring to the drawings, the multiple folds of paper designated E are placed in the base container A on top of the carbon sheets C'. The second or inner cover B has a slot opening S at the top near one end through which the continuous reel or fold of paper is threaded and extended along the top Q. The top Q we prefer to construct of some metallic substance, inasmuch as it forms the writing base for the paper. After the multiple copies of the folded paper E are threaded through S along the top Q of the cover B, provision is made for bringing the carbon paper C' out through the side slot F of the base A at the bottom, around the outside of B, and between the folds of E. The slot T is cut in each of the three covers for a thumb insertion to facilitate threading the papers properly through the entire device. After the paper is threaded our final cover C is placed over the entire case. Cover C is provided with a rectangular opening O, so that writing may be placed on the paper forms E, also a slot or holes are provided at L to enable the flexible hook J with its pointed ends to protrude through the holes in the paper and hold it in a firm position. J is operated by the handle K, merely by pulling it up and down. Its other or rearward end is inserted between the inside cover C and the inside cover B through a slot in C. It

may also be fastened by other suitable means. Also the cover C is provided with a protrusion extension G, preferably made of metallic material, so that the paper as it is drawn off may be torn or cut along the edge of G, while it is held in the proper position by the lugs of J protruding through the slot or holes L. Also the cover C is cut or slotted beneath the lug G to permit of the passage of the paper folds to the outward side of the container. We also provide the indentations D in order to give more friction and rigidity to the several covers when they are in position. It will be seen that when our device is being operated the paper E may be pulled from underneath the lug G by releasing the holder J until the next series of multiple forms is in position, at which time J may be released for engagement through L and the used portions of the forms torn off along the lug G. After the container A is empty the covers B and C or B or C are readily removed to another container. The containers A holding the paper are preferably sold and distributed in that fashion, with the cover B in place. When used they are merely provided with the cover C so that no further machine or apparatus of any kind is required.

Having thus described our invention what we claim and desire to secure by United States Letters Patent is:

A container of the type described having a base adapted to contain multiple fold continuous form paper together with carbon sheets, a cover slotted to permit of the withdrawal of said folded forms along its top surface said paper having slotted portion to permit of the withdrawal of said carbon paper at its base, the whole enclosed by an outer cover having a writing access opening above said forms provided in the top of said outer cover.

In witness whereof we have hereunto signed our names this 20th day of August, 1926.

JOHN D. WALSH.
LOUIS C. ANTRIM.
